METAL CONTAINER

Ronald L. Wakelee, Chicago, Ill., assignor to
 Continental Can Company, Inc., New York,
 N. Y., a corporation of New York

Application February 20, 1935, Serial No. 7,410

1 Claim. (Cl. 220—27)

The invention relates to new and useful improvements in a metal container of the friction closure type, and more particularly to a container wherein a frangible sealing member is used in conjunction with the friction closure.

An object of the invention is to provide a container of the above type wherein the frangible sealing member is disposed outside of the friction closure and secured to the can top by a shaping of the metal of said can top to provide a clamping means therefor.

A further object of the invention is to provide a container of the above type wherein the can top is bent upwardly and thence laterally for the purpose of clamping the sealing member to the can top.

These and other objects will in part be obvious and will in part be hereinafter more fully disclosed.

20 Referring to the drawing—

Figure 1 is a view partly in side elevation and partly in vertical section showing the container embodying the improvements of the invention;

Fig. 2 is an enlarged partial vertical sectional view of the container showing the friction closure and frangible sealing member in place; and

Fig. 3 is an enlarged vertical sectional view similar to Fig. 2, but showing a slightly modified form of friction closure.

The invention relates particularly to metal containers of the friction closure type having a frangible sealing member used in conjunction therewith. The container comprises a body portion preferably of metal having ends double seamed thereto, one of said ends being in the form of a container top having a central opening and a vertical friction wall surrounding said opening. A friction closure is provided for the container, said closure being adapted to frictionally engage the vertical friction wall of the container top for closing the container. A frangible sealing member or disk is used in conjunction with the friction closure. Said disk is disposed so as to overlie said friction closure with the peripheral edge portion thereof contacting with the container top between the vertical friction wall and the double seam. The container top has a portion of the metal thereof bent upwardly and thence laterally to form a clamping member for clamping the frangible sealing disk against the face of the container top. A suitable sealing compound is used in the region of the clamping member for assuring an airtight seal for the container.

55 Referring more in detail to the drawing, a

container embodying the invention is indicated at 4. The container is preferably of metal comprising a body portion 5 having a bottom end 6 double seamed thereto as indicated at 7, and a top end 8 secured thereto by a double seam 9. 5 The top end 8 or container top as it is usually called, has a central opening with a vertical friction wall 11 surrounding said opening. The vertical friction wall terminates at its lower end in an inturned strengthening bead 12. A friction closure 13 is provided for the container having a depending vertical friction wall 14 which is adapted to frictionally engage the friction wall 11 of the container top for closing the container. The friction closure 13 is provided with an outwardly turned laterally extending hollow bead 15 at its upper end which is adapted to overlie and contact with the container top 8 adjacent the central opening therein.

A frangible sealing member or disk 16 is used 20 in conjunction with the friction closure 13 for further sealing the container. This frangible sealing disk is preferably made of aluminum, but might be made of any other frangible material, such as tagger's tin, paper or the like. The disk 25 16 is of such diameter as to be adapted to completely overlie the friction closure 13 and have the peripheral edge portion 17 thereof extend beyond the bead 15 on the friction closure and contact with the upper face 8a of the container 30 top between said bead and the double seam 9 at the top of the container. The container top 8 has a portion of the metal thereof bent upwardly as indicated at 18 and thence laterally as indicated at 19 to form a clamping member 20 for 35 clamping the peripheral edge 17 of the disk against the upper face 8a of the container top. A suitable sealing compound 21 is placed beneath the sealing disk and adjacent the clamping member 20 for producing an airtight seal for 40 the container.

In the form of the invention shown in Fig. 3 of the drawing, a slightly modified form of container embodying the invention is shown. The vertical friction wall at the lower end thereof is turned outwardly into a bead 12a and a modified form of friction closure 13 is employed. The portion of the metal at the lower end of the depending friction wall 14 of the closure extends 45 inwardly, upwardly and thence outwardly, forming a raised flat central portion 22 which lies substantially in the plane of the top bead 15 at the upper end thereof. In this form of friction closure, additional protection is given to the fran- 50 55

gible sealing disk against accidental rupturing during handling.

In manufacture, the containers disclosed by this invention are made in the following way.

- 5 The friction closure 14 is inserted within its seat and the sealing disk 16 is placed over said closure. The clamping member 20 is then bent down upon the peripheral edge of the sealing disk, thus drawing it tightly over the friction closure 14 and the top 8 is secured to the end of the can by the double seam 9. The lower end of the container is left unsealed and the container in this form is thus shipped to the packer, who, after the container is filled, closes the bottom end thereof with the usual top or bottom 6, as indicated in the drawing.

When it is desired to open either type of container disclosed in the invention, a knife or other sharp instrument is used to cut away the frangible disk and the friction closure may then be removed in the usual manner.

From the above it will be apparent that a container has been devised wherein an airtight seal has been provided for a container of the friction closure type, and wherein the removal of the frangible disk used in conjunction with the friction closure would readily indicate tampering with the contents of the container.

It is obvious that minor changes in the details of construction and the arrangement of the parts may be made without departing from the spirit of the invention as set forth in the appended claims.

Having thus described the invention, what I claim as new and desire to secure by Letters Patent, is—

A metal container comprising a body portion having a container top secured thereto by seam-10 ing, said container top having a central opening surrounded by a vertical friction wall, a friction closure adapted to engage said vertical wall in the container top, said closure having a curved flange projecting over and containing with the 15 container top, a frangible sealing disk extending across said friction closure on the outer face thereof and having its peripheral edge contacting with the container top in the region between the friction wall and the seam, said container top 20 between said friction wall and the seam being bent upwardly to form a fold in the metal, and said folded portion of the metal being turned downwardly to contact with the sealing disk for clamping the same to the can top. 25
